CLAIM

The ornamental design for a door lock, as shown and described.

DESCRIPTION

FIG. 1 is a top, front, right side perspective view of an embodiment of a door lock;

FIG. 2 is a top, front, left side perspective view of FIG. 1; FIG. 3 is a front elevation view of FIG. 1;

FIG. 4 is a rear elevation view of FIG. 1;

FIG. 5 is a left side elevation view of FIG. 1;

FIG. 6 is a right side elevation view of FIG. 1;

FIG. 7 is a top plan view of FIG. 1; and,

FIG. 8 is a bottom plan view of FIG. 1.

The dash-dash broken lines show portions of the door lock that form no part of the claimed design. The dot-dash broken lines represent boundaries of the claimed design and form no part of the claimed design. Any broken line illustration of environmental structure in the drawing is not part of the design sought to be patented.
